William Arnold

United States Patent Office.

WILLIAM ARNOLD, OF PAWTUCKET, RHODE ISLAND.

Letters Patent No. 96,864, dated November 16, 1869.

IMPROVED WASHING-MACHINE.

The Schedule referred to in these Letters Patent and making part of the same.

To all whom it may concern:

Be it known that I, WILLIAM ARNOLD, of Pawtucket, in the county of Providence, and State of Rhode Island, have invented an Improved Washing-Machine; and do hereby declare that the following is a full and correct description, reference being had to the accompanying drawing, making a part of this specification.

The nature of my invention consists in furnishing an additional bearing or step below the wash-wheel, with projecting ring, when attached to a movable cover; also, in placing a centre-piece between the revolving pins, so that the clothes may move in an annular space, and also come in contact with vertical rolls or corrugations.

To enable those skilled in the art to make and use my invention, I will proceed to describe its construction and operation.

Figure 1 represents a sectional side view, and

Figure 2, a top view of the suds-box.

The wash-wheel A, with its projecting pins *a a*, is to be revolved back and forth by means of the crank B, and bevel-gears C C, being attached to the hinged cover D.

The lower end of the shaft E enters the step *g* at the top of the centre-piece F.

This centre-piece may be made slightly conical, as represented, and may be either held fast to the bottom of the suds-box, or it may be allowed to turn loosely, as around a central spindle, G.

The shaft E, which carries the wash-wheel, is also supported by a bearing, *h*, above the gear.

In the corners of the suds-box, as shown in fig. 2, I place vertical rolls, as *b b b*, or vertically-fluted boards, *d d*.

This arrangement tends to give a rubbing action upon the clothes, the centre-piece F occupying the centre of the machine, so that the clothes are kept close to the sides of the suds-box.

What I claim as my invention, and desire to secure by Letters Patent, is—

The arrangement and combination of the crank B, gears C C, wash-wheel A, with its projecting pins *a a*, and centre-piece F, with its step *O*, as specified.

Also, the combination of the wash-wheel A, centre-piece F, step *O*, in combination with rolls *b b b*, or corrugated corner-boards *d d*, as described.

WILLIAM ARNOLD.
